UNITED STATES PATENT OFFICE.

ALFRED KURTZ, OF BROOKLYN, NEW YORK.

SEWING-MACHINE ATTACHMENT.

1,277,954.

Specification of Letters Patent. Patented Sept. 3, 1918.

Application filed January 20, 1917. Serial No. 143,430.

To all whom it may concern:

Be it known that I, ALFRED KURTZ, a citizen of the United States, and a resident of the city of New York, borough of Brooklyn, in the county of Kings and State of New York, have invented a new and Improved Sewing-Machine Attachment, of which the following is a full, clear, and exact description.

10 Among the principal objects which the present invention has in view are: to provide for feeding in independently guided relation a plurality of materials or layers of material in the path of, for operation 15 upon by, the needle of a sewing machine; to provide means for feeding said material, which means permits of turning or deflecting the material so that the needle follows a curved or sinuous path; to provide for 20 delivering between the layers of the material when being sewed, a filling member; to arrange the attachment referred to so that it may be disconnected to permit the ordinary operation of the machine; and to employ a sewing machine for stitching the 25 fulled or Shirred side, smooth tip and cord for seam combined in hat linings of conventional form.

Drawing.

80 Figure 1 is a perspective view of a fragment of the head of a sewing machine, showing the end of a needle bar having a needle therein, the end of a presser-foot and feed 85 table with feed dogs therefor, and an attachment connected with said presser-foot, said attachment being constructed and arranged in accordance with the present invention;

40 Fig. 2 is a top plan view, on an enlarged scale, of said attachment, the dotted lines in said figure showing the inactive position to which a portion of the attachment may be moved;

45 Fig. 3 is a longitudinal section taken as on the line 3-3 in Fig. 2, the figure being also employed to show the materials being fed thereto;

50 Fig. 4 is a cross section taken as on the line 4-4 in Fig. 2, showing in conjunction therewith the material which is guided and fed by the attachment;

55 Fig. 5 is a cross section taken on the line 5-5 in Fig. 2;

55 Fig. 6 is a detail view showing in plan a modified form of that portion of the at-

achment employed for guiding the corded material;

Fig. 7 is a perspective view showing a hat lining in the construction of which the present attachment is employed;

Fig. 8 is a detail view, on an enlarged scale, showing in section a fragment of the lining:

Fig. 9 is a detail view in section, showing a hat lining having a corded edging of conventional construction;

Fig. 10 is a detail view, on an enlarged scale, showing the disposition of the materials employed in the construction of hat linings arranged as delivered to the needle of the sewing machine;

Fig. 11 is a detail view in section, showing a corded edging to secure which in the lining the attachment is employed;

Fig. 12 is a detail view showing fragments of the side member and tip of a hat lining arranged in connection with a cord filler for the same between said member and said tip;

Fig. 13 is a bottom plan view of the edging guide tube;

Fig. 14 is an end view of the same, showing in connection therewith a corded edge strip;

Fig. 15 is an end view of a feed tube constructed in accordance with the modified form.

Description.

As seen in the accompanying drawings, the attachment embodies a shortened sewing machine presser-foot 17. The foot 17 has a slotted shank 18 provided with a bifurcated end 19, between the members 95 whereof rest a set screw 20 and a presser-foot bar 21. The foot 17 has a shortened body, at the forward end whereof an opening 22 forms a passage for a sewing-machine needle 23. The sole 24 of the foot 17 is 100 shortened to limit the pressure area exerted thereby on the cloth between the same and the feed dog 25 of the sewing machinery. The diminished area thus provided facilitates the turning of the material as the same passes the needle. This operation is also facilitated by the fact that the sole 24 is at the far side of said needle.

In lieu of the elongated foot structure with which the usual sewing machine is provided, the present attachment is supplied with a spring foot 26, which normally ex-

tends in line with the foot 17 and is structurally connected therewith by means of a reach bar 27. The spring foot 26 normally rests above a reciprocating dog 28, which is operatively connected with the driving mechanism of the sewing machine to be moved to and from the feed dog 25. The dogs 25 and 28 are of conventional construction, being employed in what are known as 10 stirring attachments for sewing machines.

The stirring which results from the operation of the dog 28 and spring foot 26 is produced in the side body 29 of the hat lining, as seen best in Figs. 7 and 9 of the 15 drawings. In Fig. 2 of the drawings the side body 29 is indicated by dotted lines to show the straight-line feed of the material forming the side body, to the sewing machine. When being thus fed, the material 20 of the side body 29 is supported by an apron 30, and is guided by the curved wall 31 thereof. The material of the side body 29 is also guided by the foot 32 of a gage plate 33.

25 The plate 33 is slotted lengthwise to receive a block 34, as shown best in Fig. 4 of the drawings. The block 34 has a screw 35, which is engaged by a nut 36, the manipulation of which clamps in set position the 30 plate 33. As shown best in Fig. 4 of the drawings, the foot 32 serves as a guide for the material of the tip 37, as well as for the material of the side body 29.

The tip 37, as shown in the drawings, is 35 preferably constructed of two or more layers of material. The usual construction provides two layers, one of which is a facing and the other a stiffening material, such as buckram, hair-cloth or other suitable material for holding the tip in its panel-like shape. The materials, when disposed in layer form, are fed to the needle 23 of the sewing machinery, and to the foot 17 above a tube 38 and the tip 39 thereof. The foot 45 32, as above stated, operates as a guide or gage for positioning said tip.

Between the tip 37 and the side body 29, and between the edge margins thereof, is disposed the doubled thickness of the edging 40. The edging 40 is fed through the tube 38, and is guided by the wall 41 thereof and by the tip 39, which presses upon the edging 40 in juxtaposed relation to the cover 42 of a cord 43. Where the cord is sewed to 55 the edging 40, it is exposed, as shown in Fig. 11 of the drawings, the tip 39 serves to guide the same by means of said edging 40.

The cord 43 and cover 42 therefor are guided as shown best in Fig. 2 of the drawings, so that the needle 23 passes the cord at the outside thereof. To assist the tip 39 in guiding the covered cord 43, there is provided a jaw 44, against which the tip 39 normally presses, and upon which the tip 60 39 presses the interposed edging 40 close to

the inner edge of the cover 42 of the cord 43. The needle 23 operates in such close juxtaposition to the tip 39 that the cord and cover therefor may be said to be positively guided up to said needle.

As shown best in Fig. 5 of the drawings, the short sole 24 of the foot 17 rests upon the corded or ridges material, with the end in view that said material may be the more readily turned in the path parallel to the 7 outer edge of the tip 37.

As shown best in Fig. 2 of the drawings, and by dotted lines therein, it is at times desired that the apron 30, tube 38 and parts connected therewith should be removed 8 from the active to an inactive position. This enables the operator to finish the cord or edging of the hat lining. To this end, the reach bar 27 is pivotally mounted on an extension 45 by a pivot screw 46. The screw 46 holds thereunder a detent spring 47, in the end whereof is disposed a handle 48. The handle 48 has a shank 49, shown best in Fig. 3 of the drawings, the end whereof extends beyond a hole in the bar 27 9 to engage a hole 50 in the extension 45. When the handle 48 and shank 49 thereof are disposed as shown in Figs. 1 to 3 inclusive, the bar 27 and parts connected therewith are held rigidly in active position. 9 When it is desired to move the same to the inactive position shown by dotted lines in Fig. 2 of the drawings, the handle 48 is lifted until the shank 49 becomes disengaged from the hole 50, when the bar 27 may be 10 swung about the pivot screw 46.

The work having been performed for which the bar 27 was shifted, the same is swung back until the shank 49 again enters the hole 50, said bar and parts connected therewith in this manner having resumed what is termed the active position.

Operation.

Having a sewing machine equipped as described, the foot bar 21 is lifted, and the material for forming the side body 29 is placed therein, said material having been threaded above the apron 30 and under the spring foot 26 until the edge of said material rests in guided relation to the wall 31 and the foot 32 of the gage plate 33. The edging 40, having attached the cord 43, is then inserted in the tube 38. When threading the edging through the tube 38, care is 11 exercised to guide the cord 43 and the cover 42 thereof against the wall 41 and the tip 39 and jaw 44. The end of the edging, having passed through the tube, is drawn under the presser-foot 17 above the side 12 body 29. The tip 37 is next inserted under the presser-foot 17, the edge of which tip rests against the foot 32 of the gage plate 33. The material of the tip 37 rests above the tube 38, extending between the same and 13

the presser-foot 17. To permit this the presser-foot is cut away at the front in the portion wherein is formed the opening 22, to form an upwardly-inclined to 51.

5 The materials having been thus adjusted, the bar 21 is released, and the presser-foot 17 permitted to grip the several mentioned materials to force the same into engagement with the dog 25. The machine is now 10 in condition to operate. As the sewing is accomplished, it will be seen that the dog 25 co-operates with the foot 17 to step by step advance the materials held therebetween, as in conventional sewing machines. Likewise, 15 in accordance with conventional machines wherein the stirring attachment is provided, the dog 28 reciprocates to and from the dog 25 under the spring foot 26, carrying forward in proper relation in full 20 portion of the material upon which it operates, this in the present case being limited to the material of which the side body 29 is constructed. Therefore, when the combined materials pass the needle 23, it will 25 be found that, when sewed, the tip 37 and edging 40 are smooth, while the side body 29 is stirred. It will also be found that the line of stitching executed by the needle 23 is accurately disposed at the outer edge of 30 the cord 43 and cover 42 thereof. Hence, when the lining is finished, as shown best in Fig. 7 of the drawings, it will be found that the seam between the side body 29 and the tip 37 is completely filled by the cord 43 and 35 cover 42 thereof.

When the cord 52 shown in Fig. 11 of the drawings, is employed, the stitching of the machine will be found close to the folded edge of the edging 40. In this form of the 40 construction, it will also be found that the cord 52 completely fills the gap of the seam between the body 29 and the tip 37, concealing in this manner the stitching uniting said body and tip.

45 Modification.

In Fig. 6 of the drawings a modification of the invention is disclosed. The modification consists in substituting for the flat tube 38 a semi-circular tube 53. The tube 53 is bent to form a flared or flattened curved receiving end 54 and a contracted delivering end 55. The edges of the material forming the tube 53 are turned in at the end 55 and joined to form a partition 56. A relatively small guide tube 57 is mounted in said tube 53 to receive and guide the cord 43 and to lead the same into the covering material as the same passes from the tube 57.

60 The tube 53, has integrally formed there-

on the tip 39 and jaw 44. The tip 39 and jaw 44 grip the edging 40 after the same has been passed through the tube 53 in surrounding relation to the cord 43, as shown best in Fig. 6 of the drawings.

65

When the machine is provided with the modification just described, it will be seen that the covering or edging 40 and the cord 43 therefor, are fed simultaneously to the machine, to be stitched between the body 70 29 and tip 37 in the manner set forth above.

Claims.

1. A mechanism for guiding corded fabric to a sewing machine needle, comprising a 75 guide tube having at the delivery end thereof a plurality of yielding members for gripping the fabric adjacent the cord thereof, said members being spaced from the line of one wall of said tube a distance equal to the 80 diameter of said cord; and a guide extension of said tube disposed in parallel relation to said yielding members and approximately co-terminus therewith.

2. A mechanism for feeding a plurality 85 of fabrics disposed in layers to a sewing machine needle, comprising a presser-foot; a feed dog for operating in conjunction with said presser-foot; a guiding attachment embodying superposed supports for different 90 layers of said fabrics; a gage plate mounted in lateral relation to said needle to form a gateway therewith, said plate being adjustable toward and away from said needle, said plate being adapted to engage and control the path of said fabrics; and a plurality of auxiliary presser-feet, each adapted to depress one of said layers, for preventing the lift thereof by said needle.

3. A mechanism for feeding a plurality 100 of fabrics disposed in layers to a sewing machine needle, comprising a plurality of presser-feet disposed in separated relation around the operating path of said needle; a plurality of feed dogs for advancing said 105 fabrics under said feet, a tubular guide member for one of said fabrics arranged for delivery thereof between two of said presser-feet for engagement by the uppermost foot; and a reach bar for supporting 110 said tubular guide member, said bar being pivotally connected to swing from the feeding path of said needle.

In testimony whereof I have signed my name to this specification in the presence of 115 two subscribing witnesses.

ALFRED KURTZ.
